UNITED STATES PATENT OFFICE

WILLIAM E. SHARP, OF CHICAGO, ILLINOIS

DESIGN FOR AN EXERCISER CASING

Application filed December 12, 1928. Serial No. 29,242. Term of patent 14 years.

To all whom it may concern:

Be it known that I, WILLIAM E. SHARP, a citizen of the United States, residing at Chicago, in the county of Cook, State of Illinois, have invented a new, original, and ornamental Design for an Exerciser Casing, of which the following is a specification, reference being had to the accompanying drawing, forming part thereof.

The figure is a view in perspective of an exerciser casing showing my new design.

I claim:—

The ornamental design for an exerciser casing, as shown.

In testimony whereof I hereunto affix my signature.

WILLIAM E. SHARP.
